ILLUMINATED HANDBAG

Edward H. Terlinde, St. Paul, Minn.

Application August 17, 1946, Serial No. 691,352

3 Claims. (Cl. 240—6.45)

1

My invention relates to an improvement in illuminated hand bag wherein it is desired to provide a means of lighting the interior of the bag.

Hand bags in use at the present time are often large and bulky and contain numerous items. Because of their size and capacity, it is often difficult to locate an article within the bag. This is particularly true in the case of keys or similar objects which are small in size and which often must be located in the dark.

It is the object of the present invention to provide a hand bag having incorporated therein a means of illuminating the interior of the hand bag. As a result objects such as keys or the like can be readily found in the dark.

A further feature of the present invention lies in the provision of a hand bag incorporating a means for providing exterior illumination when desired. As a result a light may be provided for locating a key hole, door bell button or any lost article which otherwise might be difficult to find in the dark.

A feature of the present invention lies in the fact that in preferred form my illuminating means is located in the handle of the bag. I have found that hand bags are often made with handles of wood or plastic which are of sufficient size to permit easy insertion of a battery and the like. Thus without increasing the size of the hand bag or the handle thereof, it is often possible to provide a cavity of sufficient size to receive the necessary battery and light bulb.

A feature of the present invention resides in the provision of a switch means which may be positioned exteriorly of the bag so that the light may be illuminated without opening the bag to operate a switch. It is oftentimes more simple to operate the switch while the bag is closed than after the bag is opened.

A further feature of the present invention lies in the provision of tubes of plastic or the like which are capable of conducting light to remote points within the hand bag. The hand bags are often of sufficient length so that a single centrally located bulb can not properly illuminate the entire interior thereof. Rather than to provide a plurality of light bulbs, I prefer to extend plastic tubing from the single bulb to remote points within the body of the bag so that the entire interior of the bag may be properly illuminated.

A feature of the present invention resides in the fact that the light bulb is preferably enclosed so that it can not readily be broken by

2

the insertion or removal of articles from the bag. The bulb is preferably located in a socket within the handle and will not easily be injured by accidentally striking the same.

These and other objects and novel features of my invention will be more clearly and fully set forth in the following specification and claims.

In the drawings forming a part of my specification:

Figure 1 is a sectional view through a hand bag handle showing an illuminating means incorporated therein.

Figure 2 is a sectional view transversely through the top of the bag and its handle, the position of the section being indicated by the line 2—2 of Figure 1.

Figure 3 is a perspective view of the switch which may be used to turn the illuminating means on and off.

Figure 4 is a sectional view through a modified type of bag showing the illuminating means supported therein.

Figure 5 is a sectional view through the handle, the position of the section being indicated by the line 5—5 of Figure 4.

Figure 6 is a sectional view through the handle, the position of the section being indicated by the line 6—6 of Figure 4.

Figure 7 is a perspective view of the light assembly showing the manner in which the light may be removed and replaced.

The hand bag A illustrated in Figures 1 and 2 of the drawings includes a hand bag body 10 of any convenient or preferred type. This hand bag 10 has an opening at its upper extremity, the edges of the hand bag opening being secured to a relatively rigid pair of frames 11 and 12. The frames 11 and 12 are pivotally connected at 9 and provides a means of supporting the bag body in open or closed position.

A handle 13 is pivotally connected at 14 to one frame member such as 11 and is spring urged by spring means not illustrated into engagement with a projection 15 on the frame member 12 to hold the frame members 11 and 12 in closed position. The projection 15 preferably engages into the undersurface of the handle 13 to hold the bag closed. By slightly pivoting the handle 13 about its longitudinal pivots 14, the projection 15 may be released to permit the opening of the bag. As this structure is common in hand bags of this type, the latch construction of the bag has not been illustrated in detail.

Longitudinally extending aperture 16 is pro-

vided in one end of the handle 13 extending to a point near the center of the handle. This aperture 16 is of proper size to receive a dry cell battery 17 of a type often used in small flash lights. An aperture 19 extends into the handle 13 from the lower surface thereof. The upper extremity of the apertures 19 is internally threaded as indicated at 20. A bulb 21 is threaded into the aperture 19 and is supported in fixed position therein.

The apertures 16 and 19 intersect so that the projecting fixed contact 22 of the battery 17 may engage against the threaded metal end 24 of the light bulb 21. The end or axial contact 25 of the bulb 21 is in contact with an elongated metal strip 26 positioned in a groove along the upper edge of the aperture 16. This metal strip 26 extends to a point near the outer extremity of the handle aperture 16.

The switch device of the type illustrated in Figure 3 of the drawings is engaged in the inner end of the aperture 16. This switch element is indicated in general by the numeral 27 and includes a threaded plug 29 which is designed to engage in internal threads 30 in the outer extremity of the aperture 16. A flange 31 is provided on the outer end of the plug 29 and the periphery of this flange 31 is preferably knurled to permit easy rotation thereof. A sleeve 32 is attached to the plug 29, this sleeve being of proper outer diameter to fit within the aperture 16. A spring 33 is mounted within the sleeve 32 and is terminally connected at its inner end by a connection 34 extending through the sleeve to an external contact 35 on the surface of the sleeve 32. This external contact 35 extends longitudinally of the sleeve 32 and is provided with an arcuate end 36 extending a portion of the periphery of the sleeve 32.

In operation the sleeve 32 is rotated by the flange 31 until the contact 35 or its segment 36 engages the elongated metallic contact strip 26. As soon as electrical contact is made between the contact 35 and the strip 26, a circuit is completed from the rear end of the battery 17 through the spring 33 and the connection 34 to the contact strip 35. The circuit further extends through the elongated strip 26 to the axial contact of the light bulb 21. The metallic strip or sleeve 24 of the light bulb 21 which forms the second bulb contact is in engagement with the other pole 22 of the battery 17. Accordingly as long as the contact 35 or its segment 36 is in engagement with the strip 26 the light bulb 21 will be illuminated. As soon as the flange 31 is rotated to disengage the contact between the strip 26 and the contact 35, the circuit to the light bulb 21 is broken.

For the purpose of decoration, a plug 37 having an external flange 38, similar to the flange 31, may be supported in the opposite end of the handle 13 so as to make the handle symmetrical in appearance. The plug 37 has no utility in the operation of the illuminating means.

As will be best illustrated in Figure 1 of the drawings a pair of plastic rods 40 and 41, which may be composed of Lucite or a similar plastic capable of conducting light around corners, extend through elongated apertures 42 and 43, respectively, in the handle 13. These rods 40 and 41 are provided with downwardly extending ends 44 and 45, respectively, which extend into the body of the hand bag 10 to assist in illuminating the interior thereof. The rods 44 and 45 may extend to a point near the bottom of the bag or may terminate in a downwardly inclined position as illustrated so as to direct light toward the bot-

tom of the bag near the ends thereof. In view of the fact that the rods 40 and 41 terminate adjacent the light bulb 21 and as the apertures 42 and 43 intersect the rear aperture 19, light from the bulb 21 may be conducted into the interior of the bag through the rods 40 and 41 near the bulbs 21 to illuminate the opposite end portions of the bag interior.

As indicated in Figures 1 and 2 of the drawings the frame member 14 is provided with a notch 46 therein immediately beneath the aperture 19. This notch 46 permits the light from the bulb 19 to be directed downwardly into the interior of the bag. Thus when the bag is opened the light from the bulb 19 will act to illuminate the interior of the bag and permit the distinguishing of the various articles therein.

As illustrated in Figure 2 of the drawings the plastic handle 13 may be provided with a recess or aperture 47 therein. This aperture is either provided in the exterior surface of the handle 13 to extend into close proximity with the aperture 19 or else communicates with the aperture 19 leaving a relatively thin wall 49 of plastic between the bulb 21 and the exterior. As a result the light from the bulb will shine through this relatively thin wall of plastic to permit a beam of light to shine externally of the bag. When it is desired to locate some object in the dark, it is only necessary to close the circuit to the bulb 21 and to direct the beam of light passing through the thin plastic wall 49 in the desired direction.

In Figures 4 through 7 of the drawings I disclose a modified form of hand bag construction illustrated in general by the letter B. This hand bag B is provided with a body 49 which may be similar to the hand bag body 10 previously described. The body 49 is provided with an opening at the top thereof, the edges of the opening being bound by frames such as the frame 50. A handle illustrated in general by the numeral 51 is secured to the frame 50 by means of which the hand bag can be carried.

The handle 51 illustrated in the drawing is formed of metal or electrically conductive material. Obviously, however, the handle 51 could be formed of other material without greatly affecting the operation of the apparatus. The handle 51 is provided with hollow ends 52 and 53 and a hollow enlarged body 54 intermediate the ends. The body 54 is provided with a substantially rectangular aperture 55 therein near the top of the handle. A plate 56 which may be curved to conform with the curvature of the rest of the handle is provided to close the aperture 55. This plate 56 is provided with an off-set lip 57 at one end thereof designed to engage beneath the handle body adjacent one end of the aperture 55. A lip 59 is provided on the plate 56 at the other end thereof, this lip 59 being designed to extend into the end of the aperture opposite that engaged by the lip 57. A projection 60 on the plate 56 overlies a portion of the surface of the handle adjacent the last named end of the aperture 55 to permit removal of the plate when desired.

A pocket 61 is provided in the handle adjacent the aperture 55. The pocket 61 is formed by a pocket base member 62 and a pocket end 63. The pocket 61 is of proper size to contain a battery 64. A spring 65 is interposed between one end of the battery 64 and the metal end 63 of the pocket, thus forming one contact for the battery 64 and connecting this terminal of the battery to the metallic bag handle.

A socket 66 of insulating material is mounted upon the undersurface of the plate 56. This socket 66 is provided with a slot 67 in one side thereof. The socket 66 is internally threaded to accommodate a bulb 69. The slot 67 is of sufficient size to permit the projecting end 70 of the battery 64 to engage against the metal threads 71 of the bulb 69, thereby connecting these metal threads to one terminal of the battery 64.

A spring strip 72 is secured to the plate 56 by 10 any suitable means such as rivets 73. This spring strip 72 is provided with a bent contact end 74 designed to engage against the axial contact 75 of the light bulb 69. The button 76 is supported by the spring strip 72 and extends 15 through the aperture 77 in the plate 56. By depressing the button 76 the contact end 74 of the strip 72 may be flexed into engagement with the axial contact 75 of the bulb 69, thereby closing a circuit with the battery to illuminate the bulb 69. The circuit extends from the battery 64 through the spring 65, the pocket end 63, the plate 56, strip 72, to one contact 75 of the bulb 69. The other contact 71 of the bulb 69 is in 20 electrical contact with the second terminal 76 of the battery 64.

An aperture 79 may be provided through the handle body immediately below the light bulb 69 to permit light therefrom to be directed downwardly into the body of the bag B, when the bag is open. An opening 80 is provided in the side of the handle body opposite the bulb 69 so that light may be directed through the handle of the bag when desired.

To assist in illuminating the interior of the bag I prefer to provide curved plastic strips 81 and 82 which extend from a point close to the bulb 69 to a point within the body 49 of the bag B. The rods 81 and 82 are supported with one end 83 and 84 respectively in close proximity with the bulb 69 so that light emanating from this bulb will be directed longitudinally through these plastic rods 81 and 82. The lower extremities 85 and 86 of the rods are positioned near the ends of the bag B so as to direct light toward the bottom of the bag near the ends thereof. The plastic rods extend through the hollow side portions 52 and 53 of the handle 51 to enter the body of the bag.

The manner in which the interior of a hand bag may be illuminated has been described in detail. I prefer to provide a means of directing light directly into the bag from the bulb and also desire to provide a means of conducting light into the body of the bag through plastic rods capable of bending the rays of light. As a result there is no danger of breaking the bulb when placing articles into the bag or removing them therefrom and the rods 81 and 82 which do extend into the bag body are not easily damaged or broken.

In accordance with the patent statutes, I have described the principles of construction and operation of my illuminated hand bag, and while I have endeavored to set forth the best embodiment thereof, I desire to have it understood that obvious changes may be made within the scope of the following claims without departing from the spirit of my invention.

I claim:

1. An illuminated hand bag comprising a hand bag body, a light bulb supported thereby, a current supply means electrically connected to said light bulb to supply current thereto, and plastic rod means capable of conducting light supported adjacent said light bulb to receive light therefrom, said plastic rod means extending toward the ends of said bag body said rods being formed to direct light inwardly from opposite ends of the bag.
2. An illuminated hand bag comprising a hand bag body, a handle supported thereby, a light bulb supported by said handle, plastic rod means capable of conducting light, said rod means extending from a point adjacent said light bulb into the interior of said bag.
3. An illuminated hand bag comprising a hand bag body, a handle therefor, a light bulb supported by said handle, and a pair of plastic rods capable of transmitting light, said rods being supported with one end of each of said rods adjacent said light bulb, and the other end of each rod positioned within said bag body said rods being formed to direct light inwardly and downwardly from near the bag ends.

35

EDWARD H. TERLINDE.
